Thomas Mills & Bro. Same place,
Letters Patent No 2462, Dated Sept. 25. 1866.

Design for a Candy Figure

The Schedule referred to in the aforesaid Patent and making part of the same.

To all whom it may concern,

Be it known that I Leonhard Schulze of the City of Philadelphia, and State of Pennsylvania, have originated and designed a new Figure for Castings in Candy, of which the following is a full and exact description, reference being had to the accompanying photograph making part of this Specification.

The Design relates to that class of Figures which are cast hollow of transparent or opaque candy and are extensively used as toys for ornamenting Christmas trees etc. They are made by pouring the heated liquid candy into a metallic mould; after that portion of the candy which comes in contact with the mould has crystallized and hardened to form a shell of sufficient strength, the inner, yet liquid portion is poured out again, and the hollow casting is then removed from the mould which is to this end arranged to separate in two or more parts.

The Figure represents a Steam Boat, the general shape and details of configuration, being fully shown in the accompanying photograph.

What I claim as my invention and desire to secure by Letters Patent, is
The Design for a Candy Figure herein set forth.

W. F. Goss
